UNITED STATES PATENT OFFICE

143,777

DESIGN FOR A WRENCH

August A. Westman, Carnation, Wash.

Application March 27, 1945, Serial No. 118,734

Term of patent 14 years

(Cl. D54—16)

To all whom it may concern:

Be it known that August A. Westman, a citizen of the United States, residing at Carnation, Washington, has invented a new, original, and ornamental Design for a Wrench, of which the following is a specification, reference being had to the accompanying drawing, forming a part thereof, in which:

Figure 1 is a perspective view of a wrench showing my new design; and

Figure 2 is a view in elevation of the wrench shown in Figure 1 with the jaws in closed position.

I claim:

The ornamental design for a wrench as shown.

AUGUST A. WESTMAN.
